UNITED STATES PATENT OFFICE.

EDWARD H. LORENZ, OF HARTFORD, CONNECTICUT, ASSIGNOR, BY MESNE ASSIGNMENTS, TO THE NOISELESS TYPEWRITER COMPANY, OF MIDDLETON, CONNECTICUT, A CORPORATION OF CONNECTICUT.

TYPE-WRITING MACHINE.

1,122,775.

Specification of Letters Patent.

Patented Dec. 29, 1914.

Application filed June 5, 1908. Serial No. 436,743.

To all whom it may concern:

Be it known that I, EDWARD H. LORENZ, a citizen of the United States, residing at Hartford, in the county of Hartford and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and particularly to that class of machines employing straight thrust type bars.

15 The present invention embodies improvements over the type bar actuating mechanism disclosed in the patent to Wellington P. Kidder, No. 567,241, patented September 8, 1896.

20 One of the objects of the invention is to improve the touch in the key actions of typewriting machines of the above character.

Other objects will be in part obvious and in part pointed out hereinafter.

25 The invention accordingly consists in the features of construction, combinations of elements and arrangement of parts which will be exemplified in the construction hereinafter set forth, and the scope of the application of which will be indicated in the following claims.

In the accompanying drawings, wherein is illustrated one of the various possible embodiments of my invention, Figure 1 is a 35 view taken longitudinally through a typewriting machine embodying the invention, the parts being shown in normal position; Fig. 2 is a similar view showing the positions assumed by the parts when a type bar 40 is projected to impression; Fig. 3 is a similar view, but showing a type of actuating cam such as is shown in the patent to Kidder, No. 567,241. Figs. 4, 5 and 6 are, respectively, construction, displacement and 45 velocity diagrams graphically illustrating certain distinctive features of the type action.

Similar reference characters refer to similar parts throughout the several figures of 50 the drawings.

Referring now to the drawings, 1 denotes a portion of the framework of a typewriting machine, and 2 represents a bed which supports and across which slides a plurality of

type bars, one of which is shown at 3. 55 These type bars are disposed in arcuate form upon the bed, and are directed to a common point on the platen 4, which is shown disposed in front of and in contact with a platen roll, shown conventionally at 5. 60

The key levers, one of which is shown at 6, extend through slotted comb members 7 and are pivoted upon a knife edge fulcrum 8 supported in the frame work of the machine, and are held in normal position and 65 returned to such position when depressed by means of springs, such as shown at 10. Upon a ledge 11 formed upon the front wall of the frame work of the machine, are supported a plurality of blocks, one of these 70 blocks being shown at 12, said blocks being adapted to be adjusted forwardly or backwardly as by means of an adjustable screw 13, and are held in any desired adjusted position by means of a clamp screw 14. One 75 of these blocks is provided for supporting the actuating mechanism for each of the several type bars.

The mechanism above described forms no part of my present invention, but a description thereof is given in order to render the objects of the invention clearer of understanding.

Swiveled upon a forward extension 15 of block 12, as by means of a pivot pin 16, is a 85 link 17, said link having pivotally attached thereto at 18 a second link 20, which is in turn pivotally connected at 21 with the key lever 3. In the present instance, link 20 is constituted by two similarly formed members 90 connected together at their pivotal portions, and also at 22 at a point intermediate their lengths, said links straddling the type bar 3 and the link 17, as shown. Links 17 and 20 constitute a toggle which, when 95 straightened, as shown in Fig. 2 of the drawings, operates to project the type bar against the platen in which position the pivotal points 16, 18 and 21 are substantially in alinement as shown. Link 17 of the toggle 100 is provided with a cam groove 23, the outer portion 24 of which is gradually curved, said groove being sharply deflected at 25, intermediate its ends and thereafter being provided with a curved portion 26, said deflected portion 26 being so disposed that the central line of the deflection, if prolonged, would pass closely adjacent the fulcrum 16. 105

I have found that the construction of the cam groove with the sharply deflected portion in contradistinction to the gradually curved cam groove of the corresponding member disclosed in the Kidder patent above mentioned, and shown at 27 in Fig. 3 hereof, presents several decided advantages, which will be more particularly pointed out hereinafter.

- 10 Pivoted to a downwardly extending portion 28 of block 12 is a lever 30, preferably formed double as shown, the outer end of said lever straddling the lower portion of link 17, and carrying a roller 31, which is located in the cam groove 23, and is adapted to traverse the same thereby to swing links 17 and 20 to the position shown in Fig. 2 to project the type bar to impression. A link 32, pivotally attached to lever 30 at 33, is provided at its lower end with a hooked portion 34 which extends through an eye 35 in the key lever and furnishes an actuating connection between said key lever and lever 30 and actuates the latter when the key lever 25 is depressed.

When the parts are in the position of rest, as shown in Fig. 1, the sharply deflected portion 26 of the cam groove is adjacent and below the roller 31 and inclines sharply 30 toward the type bar 3, and it will be seen that when the key lever is depressed thereby to swing lever 30, the cam roller 31 moves along the portion 26 of the cam groove, thence across the merging point of portions 35 26 and 24, and thereafter gradually moves outwardly to the position shown in Fig. 2, in which positions the toggle is on centers and the type bar is in engagement with the platen. The type bar, therefore, moves 40 with a gradually increasing velocity during the first portion of its movement toward the platen and with a diminishing velocity during the latter portion thereof, and is barely moving at the end of its stroke, the printing 45 being effected by pressure rather than by impact or concussion.

Referring now to Figs. 4, 5 and 6, and Fig. 4 in particular, showing diagrammatically the method of laying out the displacement diagram shown in Fig. 5, in which the line A represents the movement of the type bar divided into tenths corresponding to the movement of the key lever, which is assumed to travel at a uniform rate of speed. 50 The line B represents the movement of the type bar actuated by the cam mechanism shown in Fig. 3, assuming the same to be of one and one-half inch stroke, for convenience. The manner of obtaining the displacement of the type bar for each tenth of the movement of the key lever is in brief as follows:

In Fig. 4 the point 40 represents the pivot point about which the oscillatory cam member turns. When the type bar is in normal

or retracted position, the center line of the cam slot will be represented by the curve 53—54, in the upper position shown, the lower position representing the position of the cam slot when the type bar has been 70 moved to impression. The type bar link 44 is pivoted to the oscillatory cam member at the point 42 and to the type bar at 43. The point 43, during the stroke of the type bar, will pass along in a straight line, represented by the line A from the point 0 to the point 10, Fig. 5. At the same time the point 42 will traverse an arc 42—41 to the point 41, when the toggle formed by the oscillatory cam member and the link 44 will be 75 in extended position, or lie in the same straight line, and the type will have moved to the printing point represented by the point 10 in the displacement diagram, Fig. 5. The cam lever 30 turns about a pivot 80 point 50 and carries the roller 31 adapted to traverse the cam slot in the oscillatory cam member. This lever is adapted to swing the cam member from its upper or normal position to its lower position when 85 the type bar is projected to the printing point, as above explained, and the roller will traverse the arc represented by line 90 56—55.

The cam is composed of three arcs, the first being from 55 to 53 drawn from the point 50 as a center, so that any motion of the roller beyond the point 55 will have no effect upon the cam. Second, that from 55 to 57, drawn from the point 51 as a center, 100 and third, that from 57 to 54 having a central point 52. Let it be assumed that the distance through which the key lever moves is divided into ten equal parts. The number ten is simply assumed as a convenient 105 number of divisions. The arc represented by line 55—56 is divided into ten parts proportional to the equal divisions of the key lever dip in the following manner: Due to the relative length of the pull wire 32 connecting the cam lever 30 and the key lever 6, it may be assumed that this remains parallel to itself at all times. Therefore, by drawing a line 64—65 perpendicular to a line bi-secting the arc 55—56 this line will 110 represent the key lever dip and may be divided into ten equal parts representing the ten equal divisions of the key lever dip. By projecting these dividing points upon the arc 55—56, the arc will be divided into parts corresponding to equal depressions of the key lever. The arc 55—56 being thus divided, the remainder of the construction 115 may now be carried out as follows: Take, for example, the position of the oscillatory cam member rotating about the point 40 when in the position corresponding to the point 4 on the arc 55—56 or after the key lever has moved four-tenths of its total distance. When the center of the cam roller 31 120

is moved to this point along the above-mentioned line, since the center of the roller traverses the center line 53-54 of the cam member, this must cut the arc 55-56 at the same point. As the pivot point 42 has always a fixed relation to the cam curve 53-54, as will be clear from the construction shown in Fig. 1, the position of the point 42 can then be laid out from said assumed point 4 as follows: An arc is described about the point 40 as a center, passing through the point 4 upon the curve 55-56 representing the path through which that point of the cam center line which cuts the cam roll arc at 4 must swing, and upon this arc a line 4, 4' is laid off equal to the distance between the line 40-42 and the cam center line, represented at 58, or line 40-41 at 59. A line 40-46 is then drawn from the center 40 through this point 4', representing the position assumed by the line 40-42 when the cam center line 53-54 cuts the arc 55-56 at the point 4. The end of the line 44 denoted by the point 42 will then be at the point 46. Taking this point as a center and striking an arc having a radius equal to the line 44, the point 4 upon the line A may then be found, representing the point to which the type bar will have advanced when the cam lever 30 has moved a sufficient distance to carry the roller to the point 4, or after the key lever has moved through four-tenths of its total path of travel. In a similar manner the other points upon the line A are established for the several divisions of the key lever dip.

From the displacement diagram, Fig. 5, showing the movement of the type bar toward the printing point corresponding to the uniform movement of the key lever, may be laid off the velocity diagram shown in Fig. 6. Since the key lever is assumed to move with a uniform velocity, the distance on the displacement diagram during each equal part of the movement of the key lever will be proportional to the velocity of the type bar during that step. That is, since each tenth of the movement of the key lever is passed over in an equal interval of time, the average velocity of the type bar during that time will be proportional to the displacement of the type bar during that time. Therefore, upon the velocity diagram, Fig. 6, the different velocities of the type bar are laid off vertically upon lines located at the middle of each tenth into which the base line is divided, whereby they will represent the average velocity during that tenth. In order that the nature of the curve may be more clearly shown, these velocities are laid out as equal to twice the displacement, as found from the displacement diagram, Fig. 5. If these points, therefore, be plotted for each tenth and a curve drawn therethrough, the height of this curve above the base line

will give the proportionate velocity of the type bar at any point in its stroke. From these two diagrams, Figs. 5 and 6, the movement of the type bar resulting from the peculiar form of the cam slot may be studied.

The points in the line B shown in the displacement diagram and curve B shown in the velocity diagram are obtained in the manner above described, from a cam slot of 75 the form shown in Fig. 3, taken from Kidder Patent No. 567,241 above mentioned, the oscillatory cam member swinging through a sufficient arc, and the connecting part being so proportioned as to give the type bar an 80 inch and a half stroke. This curve is taken from the form of cam which happens to be shown in the drawings of the Kidder patent, merely as illustrative of the differences in action between the subject-matter of that 85 patent and the present invention.

Before comparing the lines represented in these diagrams, the nature of the movement of a type action of this character should be briefly discussed and some of the 90 important features to be noted, considered as follows:

1st. The type bar should travel to the end of its stroke while the cam roll has still a considerable arc to traverse in the cam, for 95 two reasons: (a) In order to print noiselessly by pressure, very great power is required at the end of the stroke, and the pressure upon the key lever must therefore be greatly reduced by moving the key lever through a comparatively long arc while the final pressure is applied during the last few thousandths of an inch of the stroke of the type bar. (b) If the type bar approaches the final pressure point too rapidly it will strike the 105 paper, before reaching that point, sufficiently hard to make an objectionable noise.

2nd. The type bar should not start with too great a velocity in order that the impact upon the finger of the operator resulting from the blow upon the key may not be 110 unpleasant.

3rd. The type bar should not change its velocity at any one point too rapidly, either in the increasing or decreasing of its rate of 115 movement.

4th. At no time should the velocity of the type bar be too high, as the consequence thereof will result in a too rapid change in velocity in order to properly slow down before reaching the end of the stroke.

The effect of the third and fourth features can best be studied from the velocity diagram. Thus, at first sight it would appear that the velocity curve represented by 125 the line B would be more desirable. That is, the action would start easily, and its high velocity and relatively rapid slowing down would be immaterial; but as a matter of fact, the curve B results in a most unpleas- 130

- ant touch, for to obtain its high velocity requires a hard initial touch which would soon tire the operator, and during the period of acceleration, as the acceleration is constant, the pressure upon the key would continue to be about the same up to the point of greatest velocity. As the type bar almost immediately begins to slow down with great rapidity, pressure upon the key to continue the movement of the type bar would be unnecessary, as the momentum of the type bar would almost carry the key away from the finger. In other words, as soon as the type bar had reached its point of highest velocity, the pressure upon the key would practically cease, so that the "feel" of the action would be as if the finger had slipped from the key, the sudden cessation of the pressure giving a most unpleasant irregularity in the stroke.
- 10 This would be especially marked in any type of action, where the acceleration continues steadily up to the point of highest velocity. On the other hand, with the curve A, it will be noted that the greatest acceleration is during the first tenth of the stroke, and while greater than the case of B, the first tenth of the movement being relatively such a small part of the total distance traversed by the key lever, the effect
- 15 thereof will be almost imperceptible to the operator and compensated by the momentum of the finger. After the first tenth, the momentum of the finger having been eliminated, the acceleration gradually decreases
- 20 until the point of greatest velocity is reached, which is considerably less than that represented by line B and earlier in the stroke; but after that point the velocity begins to diminish gradually, and obviously
- 25 at no time diminishes with such speed as in the case of the line B, so that the pressure required is practically constant. After the key lever has been depressed seven-tenths of its stroke the type bar is further advanced and has reached the point in its stroke where the printing action begins to take place.
- 30 It will therefore be seen that the reasons whereby the action represented by the curve A is preferable to the action represented by the curve B are, first, that the type bar has practically reached the end of its stroke while the key lever has yet a considerable distance to travel; second, the velocity during the first part of the movement of the type bar is less than that of the velocity of the type bar represented by the curve B; third, the velocity of the type bar is more gradual in changing, and the change at no time is sufficient to produce an unpleasant feel in the touch; fourth, the point of highest velocity of the curve A takes place nearer the beginning of the stroke than the point of highest velocity in the curve B, thereby permitting the velocity to slow

down during a greater range of movement of the type bar. These points of distinction may be shown more clearly by the following tables, in the first of which column 1 shows the distance remaining for the type bar to move during the last three-tenths of the key lever dip; column 2 the greatest displacement of the type carrier during any tenth of the key lever dip, and column 3 the greatest difference in displacement of the type bar between successive tenths of the key lever dip, these figures being given for type actions having one and one-half inch stroke:

Cam.	1.	2.	3.
A.....	.0037 inch, 25%	.36 inch, 24%	.12 inch, 8%
B.....	.0069 inch, 46%	.39 inch, 26%	.16 inch, 104%

The second table is given to show the actual movement and per cent. of the total stroke of the type carrier moved during each tenth of the key lever dip in the type action represented by line A:

Key lever dip.	Actual movement of type-bar.	Per cent.	Differ-
			Per cent.
10.....	.279	18.6	18.6
20.....	.528	41.8	23.2
30.....	.985	65.6	23.8
40.....	1.257	83.8	18.2
50.....	1.410	94.0	10.2
60.....	1.478	98.5	4.5
70.....	1.4963	99.75	1.25
80.....	1.4994	99.96	.21
90.....	1.49993	99.995	.035
100.....	1.50000	100.	.005

It will be seen from these tables that the differences are not large; nevertheless, it has been found by numerous experiments and long experience that they are of great importance, and that a long stroke action wherein these values are not within proper limits, is impractical.

It will accordingly be seen that I have provided a construction well adapted to attain, among others, all the ends and objects above pointed out in a simple, yet efficient manner.

One important advantage of the present construction over that disclosed in prior constructions such as that of the patent to Kidder No. 567,241, above mentioned, is that the action has a smooth "feel" to the touch. This result is attained, owing to the fact that the conformation given the cam groove of the toggle mechanism is such that the type bar starts slowly, attains its maximum velocity at an intermediate portion of the stroke, and then moves with a gradually diminishing velocity during the latter portion of the stroke until the types are pressed into contact with the impression surface of the platen.

Among other advantages accruing herein

are, a free running action is given to the type bar; the inertia of the type bar is gradually overcome at the beginning of the stroke thereby rendering it easy to start the same; the stroke has its greatest power at the end; and, moreover, the entire action is substantially noiseless. Still another advantage present herein is that it is possible to provide a longer stroke for the type bar and still retain in increased degree those great desiderata in typewriting machines of this character, which are essentially, smoothness and alertness of touch and a noiseless operation. The longer stroke given the type bar is, moreover, desirable in machines of the character, since an arc of larger radius is provided for receiving the faces of the types arranged upon the bed, and it is therefore possible to widen the faces of the types.

In order to avoid any chance of ambiguity occurring in this specification or in the claims, it may here be understood that by the term "sharply deflected" as used herein to describe the cam groove, is meant a cam groove of the above described characteristics and of such construction that when the key lever is depressed the type bar will be moved with a gradually increasing velocity during the first part of its movement, and with a gradually diminishing velocity during the latter part thereof in contradistinction to the gradually curved groove, such as is shown in Fig. 3 of the drawings. By the term "feel" is meant the character or quality of the resistance interposed by the key lever to the finger of the operator.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

50 1. In a typewriting machine, the combination with the platen, of a type bar, an oscillatory member having a cam groove sharply deflected near one end connected with the type bar, a key lever, and means connected with said key lever and adapted to traverse the cam groove of said oscillatory member to actuate the latter.

60 2. In a typewriting machine, the combination with the platen, of a straight thrust type bar, an oscillatory member connected with said type bar and having a cam groove portions of which are struck upon arcs having different radii and centers, a key lever, an actuating lever having means adapted to 65 traverse said cam groove, and a connection

interposed between said key lever and said actuating lever.

3. In a typewriting machine, in combination, a pressure-operated type-bar, a member connected with said type-bar having cam portions struck from arcs having different centers, a key lever, and means actuated thereby adapted to traverse said cam portions and move said type-bar at a predetermined speed.

75 4. In a typewriting machine, the combination with the platen, of a straight thrust type bar and a key lever, means for projecting the type bar against the platen, comprising a pair of pivotally connected members one of which is pivotally connected with the type bar, and the other thereof is similarly connected with a fixed portion of the framing of the machine, one of said members being provided with a cam path sharply deflected near one end, a pivotally mounted lever having a roller adapted to traverse said cam path, and a link connecting said lever with the key lever.

80 5. In a typewriting machine, the combination with the platen, of a straight thrust type bar and a key lever, means for projecting the type bar against the platen, comprising a toggle formed of a pair of pivotally connected links, one of which is pivotally connected with the type bar, and the other thereof is similarly connected with a fixed support, one of said links being provided with a cam groove a portion of which is sharply deflected with respect to the main portion of the cam, a lever having a roller adapted to traverse said cam groove, whereby said toggle is straightened, thereby projecting the type bar against the platen, and an actuating connection interposed between 90 said lever and the key lever.

95 6. In a typewriting machine, the combination with a platen of type bars adapted to coat therewith, a toggle comprising a pair of pivotally connected members, one of which is pivotally connected with the type bar and the other with a relatively fixed support, one of the members of said toggle being provided with a cam surface, the first part of which is struck on a shorter radius than the latter part, a key lever, an actuating connection interposed between said key lever and said toggle, and means for traversing said cam surface thereby to straighten said toggle and project the type 100 to printing position.

110 7. In a typewriting machine, the combination of a platen, an endwise moving type bar, a toggle, one member of which is pivoted to the endwise moving type bar, and the other member of which is pivoted to a fixed support, said second mentioned member being provided with a cam path having one end struck from a longer radius than the other, a swinging member provided with a 115 120 125 130

- roll adapted to traverse said cam path, a key lever, and a link connecting said swinging member and said key lever.
8. In a typewriting machine, the combination of a type carrier, a platen, a toggle comprising a pair of pivotally connected members, one of which is pivotally connected with the type carrier, and the other thereof similarly connected with a fixed support, one of said members being provided with an irregularly deflected cam groove in contradistinction to a cam groove having a gradually curved conformation, and means for straightening said toggle to project the type bar against the platen, comprising a swinging member pivoted upon the fixed support and having a roller adapted to traverse said cam groove, a key lever, and a link connecting said swinging member with said lever.
- 10 9. In a typewriting machine, the combination with a platen, a type bar, an oscillatory member having an irregularly deflected cam groove connected therewith, a key lever, and intermediate means engaging said cam groove and adapted to traverse the same for moving said type bar.
- 15 10. In a typewriting machine, the combination with a platen, a type bar, an oscillatory member having a cam groove sharply deflected near the first end thereof connected therewith, a key lever, and means actuated by said key lever and engaging said cam groove in normal position near the deflected portion of the groove adapted to move said oscillatory member and connected type bar with a gradually increasing velocity at the beginning of the stroke and with a gradually decreasing velocity at the end of the stroke.
- 20 11. In a typewriting machine, the combination with a platen, of a type bar having a limited path of travel, an operating member, and mechanical connections between said type bar and said operating member for moving the type bar during the first quarter-stroke of the operating member a distance of substantially one-half of its total path of travel and at its maximum velocity.
- 25 12. In a typewriting machine, the combination with a platen, of a type bar having a limited path of travel, an operating member, and mechanical connections intervening between said type bar and said operating member for advancing said type bar upward of ninety-nine and one-half per cent, of its total path of travel during the first seven-tenths of the movement of said operating member.
- 30 13. In a typewriting machine, the combination with a platen, of a type bar having a limited path of travel, an operating member, and mechanical connections between said type bar and said operating member said mechanical connection including a power multiplying means whereby the power required for the movement of the operating member during the last three-tenths of the stroke of its travel will be greatly multiplied in its application to the type bar, so that the latter, while advancing substantially one-quarter of one per cent. of its total path of travel, may produce a powerful impression on the material intervening between the printing portion of said type bar and said platen.
- 35 14. In a typewriting machine, the combination with a platen, of a type bar, an operating member, and mechanical means connecting said type bar and said operating member for moving the type bar substantially one-quarter of one per cent. of its total path of travel during the last three-tenths of the movement of said operating member.
- 40 15. In a typewriting machine, the combination with a platen, of a type bar having a limited path of travel, an operating member, and mechanical connections between said type bar and said operating member for advancing said type bar less than one-hundredth of an inch during the last three-tenths of the movement of said operating member.
- 45 16. In a typewriting machine, the combination with a platen, of a type bar, an operating member, and mechanical connections between said type bar and said operating member adapted to constantly change the velocity of said type bar, the difference between differences of the distance traveled by the type bar in any two successive tenths of the movement of the key lever being less than nine per cent. of the total distance traveled by the type bar.
- 50 17. In a typewriting machine, the combination with a platen, of a type bar, an operating member, and mechanical connections between said type bar and said operating member comprising power multiplying devices adapted to limit the movement of the type bar and press the same against the platen at the end of its limited movement, said connections adapted to move the type bar less than twenty-five per cent. of the total distance traveled thereby during any one-tenth of the movement of the key lever.
- 55 18. In a typewriting machine, the combination with a platen, of an endwise moving type bar, an actuating member, intermediate connections therebetween including a toggle, a cam path, and a member provided with a roll adapted to travel said cam path, said cam path being so shaped that during the movement of said roll over any part thereof corresponding to a tenth part of the dip of the actuating member, said cam shall cause said type bar to move less than twenty-five per cent. of its total stroke.
- 60 19. In a typewriting machine, the combi-

nation with a platen, of a type carrier, an actuating member therefor, a toggle comprising a pair of pivotally connected members, one of which is connected with the type carrier and the other with a relatively fixed part of the frame, a cam groove on one of said parts, means for moving said toggle to extended position to actuate the type bar comprising a swinging member pivoted to a relatively fixed support, and a roll carried thereby adapted to traverse a cam groove, said cam groove being irregularly curved whereby during successive tenths of the movement of the actuating member the difference between differences in the distance traversed by the type bar shall be less than nine per cent. of the total stroke of the type bar.

20. In a typewriting machine, the combination with a platen, of a type bar, a key lever, and intermediate mechanism therebetween for transmitting motion from one to the other including a cam member and a part coacting therewith, the first part of the cam being of a less radius of curvature than the latter part.

21. In a typewriting machine, the combination with a platen, of a type bar, a key lever, and intermediate mechanism therebetween for transmitting motion from one to the other including a cam member and a part coacting therewith, one end of the cam being sharply curved and the other end more gradually curved.

35 22. In a typewriting machine, the combination with a platen, of a type bar, a key lever, and intermediate mechanism there-

between for transmitting motion from one to the other including a cam member and a part coacting therewith, the portion of the cam first operative being sharply curved and the remaining portion being formed of curves of greater radii.

23. In a typewriting machine the combination with the platen, of a type bar, a key lever and intermediate mechanism therebetween adapted to transmit motion from one to the other, including a cam member and a part adapted to coact therewith, the curvature of said cam being struck from centers with varying radii.

24. In a typewriting machine the combination with a platen, of a type bar, a key lever, and an intermediate mechanism therebetween adapted to transmit motion from one to the other and move the type bar during the last three-tenths of the key lever dip substantially .25% of the total distance traveled by the type bar.

25. In a typewriting machine the combination with a platen, of a type bar, a key lever, and intervening means between the key lever and type bar adapted to move said type bar at variable speed and the greatest difference in displacement of the type bar between successive tenths of the key lever dip being substantially eight per cent. of the total distance of the travel of said type bar.

In testimony whereof I affix my signature, in the presence of two witnesses.

EDWARD H. LORENZ.

Witnesses:

C. H. WILSON,
H. M. SEAMANS.
